UNITED STATES PATENT OFFICE.

JOSEPH G. PROSSER, OF CHICAGO, ILLINOIS.

VAPOR MOTOR OR ENGINE.

Application filed December 14, 1923. Serial No. 680,738.

This invention relates to vapor motors or engines.

The present case constitutes a divisional application, in part, of my prior application filed May 6, 1922, Serial No. 558,917, for vapor motors.

The primary object of the invention is, in connection with a hollow piston of a vapor motor or engine (associated with a heating-agent) to effect removal of a heating-medium (introduced into the piston) after such medium has lost its thermal efficiency, and to return such medium either to the heating-agent or discharge it from the engine.

Another object of the invention is, in connection with a hollow piston of a vapor motor or engine, to provide for effectually draining from the piston any condensate as the same may form therein and thereby prevent accumulation of such condensate in the piston.

Another object within the contemplation of my invention is, in connection with such hollow piston, to associate therewith a hollow tail-rod; to supply a heating-medium to the piston; and to eject such heating-medium therefrom after it has lost in thermal efficiency.

In order that the invention may be more readily comprehended by those skilled in the art, I have shown in the accompanying drawings a plurality of embodiments and applications thereof; but it is to be understood that these drawings are merely illustrative, that other embodiments and applications are contemplated, and that a wide range of modification and variation in the illustrated embodiments may be made without departing from the spirit of the invention or sacrificing any of its salient features and underlying principles.

In these drawings:

Figure 1 is a view in vertical longitudinal section through a horizontal engine-cylinder and including one embodiment of the invention;

Fig. 2 is a fragmentary view in enlarged section of a portion of the piston thereof;

Fig. 3 is a similar view, on the line 3-3 of Fig. 2;

Fig. 4 is a view in vertical longitudinal

section through a vertical engine-cylinder and involving another embodiment of the invention;

Fig. 5 is a fragmentary view, in section, 55 on the line 5-5, Fig. 4; and

Fig. 6 is a view in vertical section of a valve forming one feature of the structure.

In these drawings, the reference-character 1 designates an engine-cylinder, the same 60 being shown in Figs. 1 to 3 as of the horizontal type, and in Fig. 4 as of the vertical type. Each of these types includes a piston 2 reciprocable in the cylinder under the action of an elastic fluid, such as steam, adapted to 65 be introduced into the cylinder in any appropriate manner and as set forth, for instance, in my aforementioned application.

The cylinder, preferably and as shown in Fig. 1, is steam-jacketed as at 9, 15 and 16, 70 respectively. A heating-medium, such as steam, is supplied to the jackets 9, 15 and 16, respectively, through pipes 11 and 17 communicating with a steam-line (not shown). In this manner, the heating-medium is supplied to the jackets at the highest temperature available.

Another object of the invention is, in connection with the cylinder, to provide a drain-pipe 18 which communicates with the jackets by drainage-pipes 19, 20 and 21. The 80 pipe 18 preferably extends to a trap (not shown), and which may in turn discharge the heating-medium to a heating-agent, such as a boiler (not shown) to be reheated therein and returned or be discharged elsewhere.

The piston, preferably and as shown, is hollow to provide a chamber 22 constituting a jacket. Attached to the piston—in this instance, centrally of its axis—is a tail-rod 23 which, preferably and as shown, forms 90 an extension of a hollow piston-rod 24. The tail-rod is mounted in a bearing 25 which is protected by a gland 26 provided with an annular chamber 27 which, in turn, is protected by a gland 28 formed as the inner extremity of a hollow tail-rod-casing 29.

The tail-rod 23 is hollow to provide an elongated passage 30 in which a conduit 31 is mounted, the latter having a port 32 adapted periodically to register with the annular 100 chamber 27.

Leading into the casing 29 is a steam-pipe

33 connecting with a main steam-line (not shown) and through which steam is conveyed into the passage 30 in the tail-rod, into the hollow piston-rod 24, and through 6 openings—one of which (34) is shown—into the jacket 22 of the piston. The passage 30, which projects from the piston-face through and beyond the cylinder-wall, constitutes the primary conduit for supplying the heating-10 agent or fluid to the piston and to the piston-rod jackets. To provide for drainage of the passageway 30, a small opening 35 extends from the passageway 30 into the jacket 22.

Preferably and as shown, means are provided for draining the condensate from the jacket 22, such means including a discharge-conduit comprising the pipe 31, an annular channel 31^a in the piston and with which the pipe communicates, and an extension 37 that 15 extends nearly to the lowest portion of the jacket 22. The extension 37 is provided with a check-valve, shown in this instance as a ball 38 adapted to seat on the inner end of a ball-supporting element 39 threaded through 20 the wall of the piston 2, and which is provided with a duct 40 communicating with branch-ducts 41. The ball-supporting element is encompassed by gauze 42, or similar material, to prevent sediment or the like from 25 passing into and blocking the ducts 41. The ball 38 is normally maintained against its seat by a spring 43.

In this instance, the condensate in the jacket 22 is removed therefrom by pressure-35 means which operate externally of the engine and which include a trap 44 that communicates with the annular chamber 27 through a pipe 45 that is coiled, as at 46, to increase radiation.

40 Pressure is regulated in the trap 44, as by means of a pressure-regulating valve 47 on a pipe 48 extending into the trap 44 and operated through a pipe 49 which communicates with the interior of the casing 29 and which 45 operates on a diaphragm (not shown) disposed in the upper portion of the valve 47 in opposition to a spring 50 which is subject to regulation. Reduced pressure is maintained in the trap 44 either by reason of the radiation effected through the coil 46 or by the 50 regulating valve 47, or by both; such pressure being predetermined and somewhat lower than that prevailing in the jacket 22 of the piston.

55 It is to be understood that as the piston 2 reciprocates, the port 32 of the conduit, during a certain reciprocation of the piston, is brought into register with the annular chamber 27. The reduced pressure developed in the trap 44 operates to reduce that in the chamber 27 and to maintain it lower than that in the jacket 22. Therefore, as the piston reciprocates, the pressure at the opening 32 is reduced, likewise that in the conduit, where-60 upon the higher pressure in the piston forces

the condensate through the extension 37, thence into the pipe 31, thence into the chamber 27, and thence through the pipe 45 and coil 46 into the trap 44, from which it is discharged in any suitable way, as through a 70 discharge-pipe 51, and, thus, out of the engine, and returned to the heating-agent, or discharged elsewhere.

It is to be understood that the pressure in the trap 44 may be maintained at any pre-determined degree which will insure its action to effect a withdrawal of the condensate from the jacket 22 through the instrumentalities already referred to. The higher the speed of the engine and, thus, the more rapid 75 the reciprocation of the piston, the greater the required differential in pressure between the trap 44 and the jacket.

In this instance, the pipe 31 is shown with the port 32 extending upwardly so that the pipe will be caused to hold a certain amount of water which may have been drawn thereinto at any one reciprocation of the piston and which will be temporarily retained therein until, by the next reciprocation of the piston, the port 32 is brought into register with the chamber 27, whereupon it will be discharged in the manner already described. The check-valve 38 supplements this trapping 90 action in that it holds any water that may have passed into the conduit from returning to the jacket 22.

When the engine is at rest, and if the port 32 be then registering with the chamber 27, pressure from the jacket 22 will blow steadily 100 into the steam-trap 44 and keep the regulating valve 47 constantly in action; but means may be provided, such (for instance) as a valve 52 on the pipe 48, to prevent the steam from blowing away and without interfering with the functioning of the trap 44.

To provide for the drainage of the casing 29, a pipe 53 is connected thereto and with the drainage-pipe 18.

Extending into the annular chamber 27 is 110 an oil-pipe 54 communicating with a suitable source of supply of lubricant, and by which the tail-rod bearings are lubricated.

From the foregoing, it will be understood that, in this structure, I have provided means external of the engine-cylinder for effecting withdrawal of a condensate from the piston and discharging it out of the engine.

It is to be understood that where I have herein referred to "discharging condensate out of the engine" such expression, or the equivalent thereof, is intended to comprehend discharge of the condensate (or such condensate with a small amount of vapor which may accompany it) outside of the engine-cylinder. It may be returned to the boiler with the condensate from the other jackets, or even be discharged into the jackets, but should not be discharged in such way that either it or the aforementioned vapor of re-120

duced quality shall form part of the working-steam about to enter the cylinder.

The foregoing involves the subject-matter divided out of my aforementioned application and, to that extent and in respect thereto, the present case is a divisional application.

In the type of structure illustrated in Figs. 4 and 5, I have, as aforementioned, disclosed a vertical type of engine, and in which is included not only the features already described with reference to the embodiment of Figs. 1 to 3, but, also, certain other features, now about to be described:

This structure includes a working-cylinder 55 provided with jackets 56 supplied with a heating-agent through a pipe 57 connected to any suitable source of supply and drained at its lower part by a pipe 58. A piston 59 operates in the cylinder; it is formed with a chamber 60 functioning as a jacket; it has attached to one of its faces a hollow piston-rod 61 formed with a chamber 62 functioning as a jacket. A hollow tail-rod 63 projects from the other face of the piston and extends through and beyond the cylinder-wall and constitutes the primary conduit for supplying the heating-agent to the piston and to the piston-rod jackets.

By reason of the fact that the engine in the present instance is of the vertical type, a somewhat different type of discharge-conduit is preferably employed therein. Inasmuch as the tail-rod 63 is shown as in the center of the piston, the discharge-conduit used in connection therewith preferably extends from the lower extremity of the rod to a point as indicated at 64; and this conduit comprises a pipe 65 carrying at its inlet a centering-device 66 and a check-valve 67, the latter acting as a trapping-device for preventing any heating-agent that should be expelled from returning to the chambers 60 and 62 after such agent has entered the conduit. The outlet end of the pipe 65 extends through the periphery of the supply-conduit 63.

The piston-rod 61 is provided, adjacent its lower extremity, with a manually-operated drain-cock 69.

Leading out of an annular chamber 72—corresponding with the chamber 27 in Fig. 2—is a pipe 73, the purpose of which is to enable the production of a differential in pressure at the condensate-discharge, in the manner, for instance, described with respect to the embodiment of Figs. 1 to 3 or in any other suitable way. It is only necessary that this pipe shall be associated with an instrumentality—such as the atmosphere, for instance—at which the pressure will be sufficiently lower than that in the chamber 62 in the piston-rod to produce a differential in pressure and, thus, effect an expulsion of the inefficient heating-agent from the chamber 72.

Communicating with the primary conduit 63 and the chamber 60 in the piston are passageways 74 in the piston 59 whereby a heating-agent—introduced into the upper end of the conduit 63 through a casing 75 into which leads a pipe 76 connected with a suitable source of supply—is supplied to the chamber 60. Any inefficient heating-agent, such as condensate, that may form in the chamber 60 will drain therefrom through the passageways 77 into the chamber 62 and be discharged therefrom in the manner already described.

In operation, this vertical type of engine performs substantially as described with respect to the embodiment illustrated in Figs. 1 to 3. In both of these embodiments, means are provided whereby a reduced pressure at the condensate-discharge effects withdrawal of such condensate.

It is evident that in the operation of the instrumentalities for effecting removal of the condensate from the piston and piston-rod, the pressure at the outlet of the discharge-conduit is reduced periodically, as when such outlet registers with the chamber 27, after which (when the reciprocation of the piston carries the outlet out of register with the chamber 27) the pressure is restored to normal or to that in the piston-jacket and the casing 27. Were it not for the presence of the check-valves, etc., which operate as trapping-devices, as already described, the condensate would flow back into the chambers when the pressure is restored to normal, and would accumulate there before it could be finally expelled.

Wherever I have herein—as in the claims—employed the expression “condensate”, it is to be understood that this term, or any equivalent thereof, comprehends a heating-agent which has been cooled and therefore condensed, and that it may or may not be in a liquid condition.

Where I have herein employed the term “outlet to the discharge conduit” it is to be understood that this expression, or any equivalent thereof, is intended to comprehend the opening at which the heating-agent leaves the moving parts.

Where I have herein employed the term “tail-rod”, it is to be understood that this expression, or any equivalent thereof, is intended to comprehend any member which extends from a face of the piston and projects beyond the cylinder wall and moves in contact with a gland in the cylinder wall. It may partly or altogether encompass other rods of similar diameter but which other rods cannot be properly regarded as tail-rods.

Moreover, where I have herein employed the term “surface of the tail-rod,” it is to be understood that this expression, or any equivalent thereof, comprehends the periphery of the tail-rod, or any external surface

- thereof and located between its outer end and the point at which it is connected to the main-piston; but this term is not intended to include any surface on the end of the tail-rod.
- 5 Where I have herein used that term, namely, "end of the tail-rod," it is understood that it, or any equivalent thereof, is intended to comprehend the free end of the rod or that end which is not connected to the main-piston.
- 10 It will be noted that by reason of the inclusion in my engine of means for effecting withdrawal of condensate from the piston, etc., such condensate is discharged from the engine without causing the working-piston
- 15 to perform any extra work in connection therewith.

What I claim is:

1. An engine comprising a cylinder having a discharge for piston-condensate, a 20 jacketed piston reciprocable in the cylinder, a conduit for supplying a heating-agent to and maintaining it under substantially uniform pressure in the jacket of the piston and having an inlet-opening, a conduit for discharging condensate from the jacket and having an outlet-opening, a tail-rod encompassing portions of the supply and discharge conduits, one of said openings being in the outer surface of the tail-rod and the other opening being so located in respect to the end of the tail-rod that the condensate may have passage at that end during a predetermined period of the reciprocation of the piston, and means for causing the pressure in the piston 25 to expel from the engine condensate forming in the piston.

2. An engine comprising a cylinder having a discharge for piston-condensate, a jacketed piston reciprocable in the cylinder, a conduit for supplying a heating-agent to the 40 jacket of the piston, and having an inlet-opening, a conduit for discharging condensate from the jacket and having an outlet-opening, a tail-rod encompassing portions of the supply and discharge conduits, one of said 45 openings being in the outer surface of the tail-rod and the other opening being so located in respect to the end of the tail-rod that the condensate may have passage at that end when the tail-rod is withdrawn into the cylinder 50 and means for causing the pressure in the piston to expel from the cylinder condensate forming in the piston.

3. An engine comprising a cylinder having a discharge for piston-condensate, a jacketed piston reciprocable in the cylinder, a conduit for supplying a heating-agent to the jacket of the piston, and having an inlet-opening, a conduit for discharging condensate from the jacket and having an outlet-opening, a tail-rod encompassing portions of the supply and discharge conduits, one of said 55 openings being in the outer surface of the tail-rod and the other opening being so located in respect to the end of the tail-rod that the condensate may have passage at that end when the tail-rod is withdrawn into the cylinder, and means for causing the pressure in the piston to expel from the engine condensate forming in the piston. 60

In testimony whereof I affix my signature.
JOSEPH G. PROSSER.
